ELECTRIC ARC TYPE CUTTING GUN

Henry H. Jenkins, 864 W. Hacienda Drive,
Corona, Calif. 91720

Filed Sept. 30, 1966, Ser. No. 4,116

Term of patent 14 years

(Cl. D26—1)

FIG. 2

FIG. 1

FIG. 3

FIG. 4

FIG. 5

FIGURE 1 is a side elevational view of my electric arc type cutting gun;

FIGURE 2 is a top plan view of my cutting gun;

FIGURE 3 is a front elevational view of my cutting gun;

FIGURE 4 is a rear elevational view of my cutting gun; and

FIGURE 5 is a bottom plan view of my cutting gun.

The dominant features of my design reside in the portions shown in full lines. The broken line showing of an electrode in FIGS. 1, 2 and 5 is for illustrative purposes only.

I claim:

The ornamental design for an electric arc type cutting gun, substantially as shown and described.
